UNITED STATES PATENT OFFICE.

WILLIAM C. JARMER, OF CHICAGO, ILLINOIS.

WEATHER STRIP.

Application filed April 30, 1921. Serial No. 465,647.

To all whom it may concern:

Be it known that I, WILLIAM C. JARMER, a citizen of the United States, and a resident of the city of Chicago, county of Cook, and State of Illinois, have invented certain new and useful Improvements in Weather Strips, of which the following is a specification.

My invention relates to a novel weather strip for doors and the like and provides an effective and simple water tight attachment adapted to be fastened to the bottom thereof to prevent the entrance of water thereunder. My device is positive in operation, simple in construction and may be cheaply manufactured.

Other objects will appear hereinafter.

The invention consists in the combinations and arrangements of parts hereinafter described and claimed.

The invention will be best understood by reference to the accompanying drawings forming a part of this specification, and in which,

Fig. 1 is a side view of the invention showing same attached to a door and in operative position;

Fig. 2 is a sectional view of the stop plate on the line 2—2, Fig. 1;

Fig. 3 is a perspective view of the strip and rocking plate;

Fig. 4 is a front view of a door and door frame with the invention applied thereto and in operative position;

Fig. 5 is a sectional view on the line 5—5, Fig. 3.

The invention preferably consists of a supporting strip having closure engaging means, such as a flange 1 which may be perforated as at 1^a for the passage of screws 2 to secure the device to the door. The flange 1 may be of any suitable width so as to provide a firm support for the device. The strip is preferably bent outwardly as at 3 a suitable distance from the lower end of the supporting flange 1 and then bent downwardly to form the wall 4. The lower end of the wall 4 is preferably bent inwardly upon itself to form a bead 5 which is slotted as at 6. An L-shaped stop 6^a is preferably secured to the inner face of the flange 1 to limit the downward movement of a rocking plate 7. The rocking plate 7 is pivoted to the lower end of wall 4 by means of a hinge member 7^a which engages the slots 6 in the wall 4, a pin 8 being inserted through the

bead 5 and the hinge member 7^a to hold the parts in position.

The plate 7 preferably has on its inner side a weighted portion 9 which normally overbalances the opposite side of the plate and holds same in raised position, the downward movement of said plate being limited by the stop 6^a on the flange 1. The outer side of the plate 7 is preferably curved downwardly as at 7^b so as to fit snugly against the door sill. The engaging end of said plate may be slightly beveled if desired to permit the door being closed without striking the end of the plate against the door frame.

The portion 9 preferably consists of several thicknesses of metal to add weight to the plate 7 on its inner side, and the hinge member 7^a is fastened adjacent the portion 9 to provide additional weight so that the inner side of the plate 7 normally holds the outer side of said plate clear of the threshold when the door is being closed.

The beveled end of the outer side of plate 7 engages a stop plate 10 as the door is being closed to move said plate into operative position. The stop plate 10 may be formed of any suitable material but preferably consists of a steel plate having a thin web 11 and large beads or flanges 12 on said web, and shaped to provide a cam surface 13 for engagement with the end of the plate 7 and also to fit snugly thereagainst and against the strip when the door is closed. If desired the stop plate 10 may be inserted in the frame of the door as this provides a neater and more durable construction.

By use of my invention, it will be seen that when the door is closed it is impossible for water to enter beneath same and should any water pass through the slots in which the hinges are mounted, it would get no further than the flange on the inclined plate. The device is positive in operation, easily applied, and neat and inconspicuous in appearance.

While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope of the appended claim.

Having described my invention, what I claim as new and desire to secure by Letters Patent is:—

The combination with a weather strip comprising a supporting member having closure engaging means, and a main portion bent intermediate its width; an over-balanced plate pivotally supported by the free edge portion of said main portion and provided with an upstanding weighted portion adapted to swing against said supporting member at the angle of said bend; of a stop plate, having a recess therein conforming

to said supporting member, and means for guiding said over-balanced plate to operative position, said stop plate acting to reinforce the end of said supporting member when said over-balanced plate swings into operative position.

In testimony whereof I have signed my name to this specification in the presence of two subscribing witnesses.

WILLIAM C. JARMER.
